DATA-STORAGE STRIP CANISTER

Jackson R. Iblings, Hollywood, and Charles T. Inatomi,
Culver City, Calif., assignors to The National Cash
Register Company, Dayton, Ohio, a corporation of
Maryland

Filed Feb. 5, 1965, Ser. No. 83,698

Term of patent 14 years

(Cl. D58—12.6)

FIG.1

FIG. 2

FIG. 3

FIG. 4

FIG. 5

FIG. 1 is a perspective view of the front, one side and top of a data-storage strip canister showing our new design;

FIG. 2 is a rear perspective view thereof;

FIG. 3 is another perspective view showing the back, the side opposite to that of FIG. 1 and the bottom thereof;

FIG. 4 is a top plan view;

FIG. 5 is a bottom plan view; and

FIG. 6 is an exploded perspective view showing the interior thereof.

The essential features of our new design reside in the portions shown in full lines on the drawing.

We claim:
The ornamental design for a data-storage strip canister, substantially as shown and described.
